UNITED STATES PATENT OFFICE.

DESIRE H. VAN HOVE, OF JACKSON, MICHIGAN, ASSIGNOR TO REYNOLDS SPRING COMPANY, OF JACKSON, MICHIGAN.

SPRING STRUCTURE.

1,424,744.

Specification of Letters Patent. Patented Aug. 1, 1922.

Application filed April 28, 1921. Serial No. 465,102.

To all whom it may concern:

Be it known that I, DESIRE H. VAN HOVE, a citizen of the United States, residing at Jackson, in the county of Jackson and State 5 of Michigan, have invented new and useful Improvements in Spring Structures, of which the following is a specification.

This invention relates to spring structures for the backs of car seats or the like.

10 One object of the invention is to provide a structure of the character stated, designed particularly to reduce the quantity of upholstering material usually employed in structures of the present character.

15 Another object resides in the provision of a back spring structure embodying among other characteristics, means whereby to prevent the sagging of the upper edge of the structure incident to weight to which the 20 upper edges of the backs are subjected by virtue of people sitting on the same and also to prevent bulging or crowding of the edges of the frames during use or during the upholstering process.

25 A still further object is to provide a resilient pliable soft spring structure for the backs of car or other seats which possess considerable pliability or softness for the ease and comfort of the rider.

30 With the above and other objects in view, the invention consists in the novel construction, combination and arrangement of parts hereinafter fully described, illustrated in the accompanying drawings and pointed out 35 in the claims hereto appended, it being understood that various changes in the form, proportion and minor details of construction, within the scope of the claims, may be resorted to without departing from the 40 spirit or sacrificing any of the advantages of the invention.

In the drawings in which like characters of reference designate corresponding parts in the several figures;

45 Figure 1 is an inverted plan view of the invention.

Figure 2 is a transverse sectional view.

Figure 3 is a fragmentary top plan view.

Figure 4 is a detail fragmentary view, 50 illustrating the connection of the stays and braces with the lower edge of the front frame.

Referring more particularly to the accompanying drawings, the back is shown as 55 having a relatively flat back portion and a

transversely curved or rounded front portion, with the front merging in its curvature from the front to the rear frame so as to provide a curved or rounded upper edge for the structure. The back frame may be 60 of any suitable character, but, as shown, it is composed of front, back and end U-shaped sheet metal sections 5, with all of the sections terminating short of one another at the corners of the back.

The character 6 indicates U-shaped spring-supporting bars, in the channels of which, and in the channels of the back frame sections 5, the springs of the structure are fitted by compression of the bars 70 to effect a firm connection between the base convolutions of the springs and the spring-supporting bars, and the back frame.

The back and the spring-supporting bars are braced by suitable braces 7, the ends of 75 which are secured in the channel-shaped front and rear back sections 5 in the same manner as are the base convolutions of the springs secured therein. As many of these brace wires 7 may be employed as may be 80 necessary, and if desired these brace wires 7 may be secured to the base convolutions of intersecting springs, as indicated at 8. Clips 9, of any suitable type, may connect adjacent spring-supporting bars 6 through the 85 corresponding base convolutions of the springs.

The front or inner frame 10 is preferably composed of wire and its upper edge lies preferably in a plane lower than the upper 90 edge of the back frame. This front frame is preferably formed upon a transverse curvature, as shown.

The springs of the structure are preferably arranged in rows and the top row of 95 springs extending longitudinally of the structure are preferably of a different shape than the remaining springs. Each spring 11 of the top row is of substantially barrel-shape. The remaining longitudinal rows of springs 12 are shown as preferably being of the double-cone type. The barrel-shaped springs 11 have their front ends secured to the upper edge of the front border wire in a peculiar manner, that is, the upper sides of the front convolutions of the barrel-shaped springs 11 are connected to the upper edge of the front frame by means of suitable clips 13 and are so sprung as to provide 105 for the curved upper edge of the structure. 110

A wire 14 is secured to the lower portions of the barrel-shaped row of springs intermediate the ends of the latter. As shown, the wire 14 is connected to two adjacent intermediate coils of the barrel-shaped springs by means of suitable clips 15 and the ends of the wire 14 are directed downwardly, as at 16, and inwardly, as at 17, and clipped, as at 18 and 19, respectively, to the end 10 spring of the uppermost row of double-conical springs. The connection of this wire 14 with the top row of springs and with the end springs of the row immediately therebeneath is such as to provide for maintenance of the top barrel-shaped springs in an upwardly sprung condition to take on the required curvature.

People sometimes sit or lean with more or less force against the upper edge of the 20 backs of car and other seats and when this is done, there is a tendency for the upper edge of the structure to sag. I therefore connect a plurality of stays 20 with the aforesaid wire 14 and with the lower edge of 25 the inner frame, as shown, so that upon weight or pressure being brought to bear on the top edge of the back the upper row of springs assume their normal positions immediately upon being released of the weight 30 by virtue of the bracing effect of the stays 20 and by virtue of the connection of the wire 14 with the end springs of the row immediately beneath the upper row of springs. It will thus be seen that the wire 14 and the 35 stays 20 coact to maintain the upper row of springs normally in position against sagging.

Braces 21 connect the upper and lower edges of the front frame, being secured there- 40 to by means of suitable clips 22. These braces are designed to prevent an upward crowding of the lower edge of the front frame particularly when the frame is being upholstered, the upholstering material being generally forced toward the top edge from the lower edge of the structure during the upholstering process. The braces 21 also serve to prevent downward sagging of the upper edge of the front frame.

50 Braces 22 connect the upper edge of the rear frame with the lower edge of the front frame, being secured to the frames by the clips 23 and 24, respectively, the connection of the braces 22 with the lower edge of the 55 front frame being at substantially the same point of connection as the braces 21. The braces 22 prevent spreading or crowding of the upper edge of the rear frame during the upholstering process.

60 To reduce the quantity of upholstering material and to prevent upholstering material finding its way between the springs, I mount a resilient wire woven fabric sheet of material 25 over the inner ends of the 65 springs and over the front frame, continuing

the same up over the outer sides of the coils of the top row of barrel-shaped springs, as shown. This sheet of material 25 has a wire 26 interlaced therewith at each side edge thereof and by means of clips 27 embracing 70 the wires 26 and the front and back frames, as shown, the mesh-sheet of material is secured to the structure. If desired, other clips 28 may be used to fasten the sheet to the upper edge of the front frame. 75

The upper or outer convolutions of the springs may be connected together and to the upper edge of the front frame by clips 28, while clips 29 may connect the upper convolutions of the springs longitudinally 80 of the structure.

What is claimed is:

1. In a spring structure for the back of car seats or the like, a substantially vertical back frame, a substantially vertical front 85 frame, superimposed rows of double conical springs extending forwardly from the back to the front frame and connected to the frames, a row of substantially barrel shaped springs disposed over the aforesaid rows of 90 springs, a wire connected to the latter springs intermediate their ends, and stay wires connected to said wire and to the lower edge of the front frame to stay and prevent sagging of the first mentioned wire or said 95 upper row of barrel shaped springs.

2. In a spring structure for the back of car seats or the like, a back frame, a front frame, rows of horizontally disposed double conical springs between and connected to the 100 frames, a row of horizontally disposed substantially barrel-shaped springs, arranged over the uppermost row of the aforesaid springs a wire connected to the latter springs intermediate their ends, stay wires connected 105 to said wire and to the lower edge of the front frame to stay and prevent sagging of the first mentioned wire or said upper row of barrel-shaped springs, and diagonally disposed stays between the front frame and 110 the rear frame.

3. In a spring structure for the back of car seats or the like, a back frame, a front frame, rows of double conical springs between the frames, a top row of substantially 115 barrel-shaped springs, a wire connected to the latter springs intermediate their ends, stay wires connected to said wires and to the lower edge of the front frame to stay and prevent sagging of the first mentioned wire or said upper row of barrel-shaped springs, diagonally disposed stays between the front frame and the rear frame, and stay wires connecting the upper and lower edges of the 120 front frame.

4. In a spring structure, a front frame, a back frame, rows of horizontally disposed coiled springs between the frames, and means connecting a plurality of coils of each spring of the top row of springs so as to maintain 130

the upper portions of such springs in an outwardly, curved, sprung condition, and thereby provide for a spring back structure having a relatively broad, rounded, resilient, 5 upper edge.

5. In a spring structure for the backs of car seats or the like, a rear frame, a front frame, a row of substantially barrel-shaped springs connected to the upper edges of said 10 frames, the coils of said springs extending in a direction transversely of the structure, means connected to the barrel-shaped springs to maintain them in a curved sprung condition and to give a relatively broad, 15 rounded, upper edge to the spring structure.

6. In a spring structure for the backs of car seats, or the like, a rear frame, a front frame, a row of substantially barrel-shaped springs connected to the upper edges of 20 said frames, the coils of said springs extending in a direction transversely of the structure, a wire connected to a plurality of coils of said barrel shaped springs at the under sides of said barrel-shaped springs intermediate 25 the ends of the latter, stay wires connected to said wire and to the lower edge of one of the frames to prevent sagging of the top edge of the structure, and other springs arranged between the said frames.

30 7. In a spring structure for the backs of car seats, or the like, a rear frame, a front frame, a row of substantially barrel-shaped springs connected to the upper edges of said frames, the coils of said springs extending 35 in a direction transversely of the structure, a wire connected to the under sides of said barrel-shaped springs intermediate the ends of the latter, stay wires connected to said wire and to the lower edge of one of the 40 frames to prevent sagging of the top edge of the structure, other springs arranged between the said frames, bracing stays connected to the opposite side edges of the front frame, and bracing stays connecting the up-

per edge of the back frame with the lower 45 edge of the front frame.

8. In a spring structure, two spaced frames, rows of springs between the frames, means connected to one of the outermost rows of springs intermediate the ends of the 50 latter to maintain the springs of such outermost rows in a sprung condition, and a stay connection between said means and one of the frames.

9. In a spring structure, two spaced 60 frames, rows of springs between the frames, a wire connected to the springs of one row and having connection with the end springs of the adjacent row and terminating thereat, and a bracing stay connected to said wire 65 and to one of said frames.

10. In a spring structure, a front frame, a rear frame, substantially parallel rows of springs connected to said frames, the springs of the upper row being coiled and 70 formed to provide a curved foundation for a resilient rounded upper edge of the structure downward and forwardly from the rear frame to the front frame and means connected to a plurality of intermediate coils 75 of the upper row of springs to maintain the latter in a sprung condition.

11. In a spring structure, two spaced frames, springs arranged between the frames, bracing stays connecting the frames, 80 bracing stays connecting the opposite edges of one of the frames, and relatively closely woven metallic meshed sheet of material stretched over one of the frames, a wire interlaced with the meshes of said material 85 at the opposite edges thereof, and clips engaging the frames and the last mentioned wires whereby to secure said material in stretched condition over the frames.

In testimony whereof I have hereunto set 90 my hand.

DESIRE H. VAN HOVE.
